(57) **CLAIM**

I claim the ornamental design for a purse, as shown and described.

DESCRIPTION

FIG. 1 is an isometric view from above and to a first side of the opened purse.

FIG. 2 is a view looking down upon the top of the opened purse.

FIG. 3 is an isometric view from a first side and front of the closed purse.

FIG. 4 is a lateral view of the front of the closed purse.

FIG. 5 is a lateral view of the rear of the closed purse.

FIG. 6 is a lateral view of a first side of the closed purse.

FIG. 7 is a lateral view of a second side of the closed purse.

FIG. 8 is a lateral view of the top of the closed purse; and, FIG. 9 is a lateral view of the bottom of the closed purse.
